UNITED STATES PATENT OFFICE

JAMES R. MCWANE, OF BIRMINGHAM, ALABAMA, ASSIGNOR TO MCWANE CAST IRON PIPE COMPANY, OF BIRMINGHAM, ALABAMA, A CORPORATION OF ALABAMA

CORE GUIDE

Original application filed March 19, 1928, Serial No. 262,683. Divided and this application filed March 2, 1929. Serial No. 343,887.

This invention relates to core guides, and aims generally to provide an improved flask primarily adapted for making cast iron pipe by the horizontal method, and having simple but rugged means for preventing longitudinal movement of the core, which would injure or destroy the casting, while permitting ready seating and removal of the core and also clamping thereof for deflection, as described 10 in Reissue No. 17,121 dated October 30, 1928.

This application is a division of my co-pending application, Serial No. 262,683, filed March 19, 1928, and the invention herein described is regarded as an improvement on the 15 flask claimed in my pending application, Serial No. 111,218, filed May 24, 1926, wherein longitudinal and lateral core guides are described.

In the accompanying drawings showing a 20 preferred form of the invention,—

Fig. 1 is a plan view of the drag section of a flask provided with the improved core guides, showing the core bars in dotted lines;

Fig. 2 is a vertical section through the drag 25 of Fig. 1, with parts broken away;

Fig. 3 is a section on line 3—3 of Fig. 1; and

Fig. 4 is a detail view of one of the yokes for 30 clamping two core bars in their seats.

In the drawings there is shown the drag section only of a flask which, in this instance, is 35 designed for the casting of four pipe lengths. A commercial flask, as shown, may make four 6-inch pipes each 16 feet long, all being of the

bell and spigot type. Necessarily there are 40 four cores used with such a flask, the cores being provided by hollow steel cylinders, termed "core bars," on which a green sand core is formed, as will be understood.

As the 45 cores must be shaped to provide a casting with a bell end, it follows that if the cores are not longitudinally centered with respect to the molds, the bell ends of the castings will be missshapen and may have areas so thin that they will break during cooling or during handling of the pipes or when they are subjected to hydraulic pressure. If the cores are not coaxial with the molds, the castings will have thin places on one side. Hence it is 50 of primary importance to space the core accu-

rately relative to the mold, or in other words, to guide it both laterally and longitudinally.

In my pending application Serial No. 111,218, core guides are shown, but said guides are complex and are very difficult to finish when on the flask section; and if the pairs of guides are provided on a member initially separate from the flask section but finally operatively integral therewith, there is much difficulty in accurately positioning said member so that the cores will be perfectly guided. According to the invention, the simplest possible core guides are employed, being integral with one of the end walls of the drag and serving as 60 abutments for the annular flanges on core bars to prevent longitudinal movement thereof inwardly; the core bar clamping and deflecting means claimed in Reissue No. 17,121 preventing outward longitudinal movement after the cores are seated, and the machined webs or 65 seats disclosed in the same reissue preventing lateral movement of the ends of the core bar.

Referring particularly to the drawings, there is shown a drag 5, having one end wall 6 provided with integral bosses 7 having 70 their outer faces 8 machined, said bosses being located preferably at diametrically opposite points, on each side of the cut-out portions 9 through which the core bars 10 project. The upper faces of the bosses are plane 75 surfaces and are flush with the top edges of the walls of the drag.

When the core bars are placed on the drag, they are supported near their opposite ends by the machined webs or seats 11, but are otherwise clear of all parts of the drag, and of course, clear of the mold itself. Each core bar has an annular flange 12 (Fig. 1) near one end which is used in holding the core bar against longitudinal movement during 80 formation of the core, as disclosed in my pending application Ser. No. 216,467, filed August 30, 1927. As each core bar is seated, the operator pushes the flanged end inwardly until the inner face of flange 12 abuts the 85 outer machined faces 8 of the bosses. As the flanges 12 are accurately located relative to the sand cores which are formed on the core bars, and are carefully machined to abut both the bosses, it follows that the cores are ac- 90

curately centered longitudinally relative to the mold, while the accurately machined seats 11 center the core bars laterally.

As disclosed in Reissue No. 17,121, the core bars are then clamped securely in their seats and are deflected at intermediate points to counteract the floating and sidewise deflecting action of the molten metal, so that as the casting hardens, the core bars are truly coaxial with the mold, or very nearly so, yielding substantially uniform castings. It has been found that any flask construction wherein no core bar clamping means is used is impracticable, even if core bar guides are employed, because of the likelihood of movement of the core bar longitudinally or laterally or both, even though initially seated and centered with the utmost care. The core bar clamping and deflecting means shown 20 consists of two yokes 13 (Fig. 4) at each end of the drag, each yoke contacting with the tops of two core bars, and being tightened by means of a bolt 14 whose opposite end passes into a slot 15 provided on a projection 16 on 25 the drag. As each bolt 14 is drawn tight, the yoke pulled down thereby will clamp two core bars against their seats thus deflecting them upwardly at intermediate points, thereby overcoming the natural sag of the core 30 bars due to their weight and the method of their support. Then the screws 17, carried by lugs 18 projecting underneath each core bar, are tightened against the undersides of the core bars, causing the core bars to be 35 deflected downwardly at intermediate points. Thus the centered core bars cannot move longitudinally in either direction, while the lateral position of the core bar is under control, as stated.

40 It will be clear that the bosses or guides 7 are very rugged and can stand a great deal of abuse without breaking off and without affecting the accuracy of the longitudinal guiding of the core bar. While two bosses 45 are shown for each core bar, the pairs of bosses could be made integral and assume the form of a single semi-circular boss, whose outer surface would necessarily be machined for contact with the circular flange of the 50 core bar, thus determining the position of the core with respect to the mold. This obvious variation needs no illustration.

The invention represents a decided advance over the construction of my pending 55 application, Serial No. 111,218 because the two vertical spaced ribs of said application are eliminated. Instead of using one pair of ribs for lateral guiding and a second pair 60 for longitudinal guiding, a single pair of strong and rugged bosses are used, and the machined seats are depended upon for lateral guiding. Thus the invention provides longitudinal guiding means far simpler of construction, much easier to make, and much

more able to withstand the wear and tear of constant use.

Obviously the invention may be embodied in other forms than the one shown.

What I claim is:—

1. A flask section for pipe and the like having an end wall provided with an outwardly projecting, integral boss, said boss having an outer machined face and being so spaced relative to the mold as to guide the core bars 70 longitudinally; the top of said boss being flush with the top of the flask section.

2. In combination, a flask section for pipe and the like having an end wall provided with an outwardly projecting, integral boss, 80 said boss having an outer machined face and being so spaced relative to the mold as to guide the core bars longitudinally; the top of said boss being flush with the top of the flask section; and a core bar having a flange 85 projecting laterally thereof for contact with the outer machined face of the boss.

3. In combination, a flask section for pipe and the like having an end wall provided with a pair of outwardly projecting bosses, 90 said bosses being at diametrically opposite points adjacent the opening for the core bar and each having its outer face machined; and a core bar having an annular flange near one end for contact with the two machined 95 faces aforesaid.

4. In combination, a flask section for pipe and the like having an end wall provided with an outwardly projecting, integral boss, said boss having an outer machined face and being so spaced relative to the mold as to guide the core bars longitudinally; the top of said boss being flush with the top of the flask section; a core bar having a flange projecting laterally thereof for contact with the outer machined face of the boss; machined seats on the flask section near the opposite ends thereof for support and lateral guiding of the core bar; and core bar clamping means located beyond the core bar seats 110 and adjacent the opposite ends of the flask section.

In testimony, that I claim the foregoing as my own, I have hereto affixed my signature.
